UNITED STATES PATENT OFFICE.

ETHEL MAY LAWRENCE, OF HAMPTON WICK, ENGLAND.

DOOR OR LIKE LATCH.

Application filed November 15, 1922. Serial No. 601,063.

To all whom it may concern:

Be it known that I, ETHEL MAY LAWRENCE, a subject of the King of England, residing at Hampton Wick, Middlesex, 5 England, have invented certain new and useful Improvements in Door or like Latches, of which the following is a specification.

This invention relates to door or like 10 latches of the type having a bolt or latching member with a bevelled surface whereby it may be forced back by a locking staple or striking plate over which the bevelled portion rubs during the relative movement that 15 takes place between the bolt and the staple or plate on the operation of closing the door or the like. Such a bolt can be improperly forced back by a gimlet, putty knife or other appliance at times when the door is not 20 open if the appliance be so actuated in contact with the bevelled portion aforesaid that there is a rubbing action between the two in imitation of that which occurs between bolt and staple in the closing of the door. 25 These bolts are usually spring-controlled and so snap back into locking position after the door or the like in being shut has moved sufficiently far to bring the bolt beyond or behind the edge of the locking staple. 30 The present invention has for one of its objects to prevent the bolt being improperly forced back in the manner aforesaid.

According to the primary feature of the present invention, there is provided a door 35 or like latch comprising a locking-staple and a spring-bolt having a bevelled surface which lies completely across the depth of the bolt and rubs over the locking-staple to force the bolt back during the operation of 40 the closing of the door or the like, said bevelled surface being so recessed as to leave ribs at its upper and lower edges and to form between them a channel and so that a portion of the bevelled surface remains for 45 presentation to a co-operating pressing surface on the locking-staple lying completely across the depth of the bolt, each rib having a groove lying in a direction transverse to that in which the bolt rubs against the 50 locking staple, which grooves open at their ends directed toward one another into said channel.

The invention also includes other means 55 of arresting the relative movement of the pressing article and the bolt and various

ways of recessing the bevelled surface of the bolt.

For a more complete understanding of the invention there will now be described, by way of example only and with reference 60 to the accompanying drawings, certain constructional forms of latch according to the invention.

In the drawings—

Figure 1 is a plan, partly in section, showing a latch according to the present invention in closing position;

Figure 2 is a face view of the construction shown in Figure 1;

Figure 3 is a view corresponding to Figure 1 of a modification; and

Figure 4 is a view corresponding to Figure 2 of the construction shown in Figure 3.

Like reference numerals indicate like parts 75 throughout the drawings.

Referring first to Figures 1 and 2, a door or the like is indicated at 10 and a co-operating frame at 11 which may be formed with a rebate into which the door swings. 80 The casing of the latch is indicated at 12 and the locking-staple at 13, the bolt 14 projecting into the interior thereof. The crack between the door and door frame is indicated at 17.

The bevelled surface 15 of the bolt is recessed to leave upstanding ribs 19 and 20. These are so arranged that when viewed end-on, as in Figure 1, the bevelled surface appears continuous. Such a bolt will be 90 forced back by a locking staple having a rubbing surface 21 which is quite sharp, and the recesses between the ribs 19 and 20 will operate to trap any such implement as a gimlet or narrow edged tool which may be 95 inserted through the crack 17 and pressed against the bevelled edge of the bolt.

In the construction shown in Figures 3 and 4 the bevelled surface 15 is recessed to leave only ribs 22 and 23 at the top and bottom edges of the bolt. In this way a housing is formed for a movable member 24 which has an extension 25 which is perforated to be threaded over the stems 26 of the bolt. The perforations are sufficiently large to 105 permit the member 24 to move a little about the stems. The springs 27 for the bolt bear against the portion 25 and tend to maintain the member 24 with its outer surface substantially in alignment with the bevelled 110

surface 15. The member 24 carries a pin 28 opposite the end of which is a slot 29 in the bolt and if the member 24 is pressed by a gimlet or other implement it will give under 5 such pressure and force the pin 28 through the slot 29. Thus, if the bolt be forced by the implement a little way back into the casing 12 the pin 28 will ultimately be brought into engagement with that casing 10 and thus positively prevent the bolt from being further withdrawn from operative locking position. To increase the protection against illicit operation of the lock, the ribs 22 and 23 may be formed with the recesses 15 situated at the portion of the bevelled surface 15 which lies adjacent the crack 17 between the door and frame. The face 18 of the locking-staple against which the bevelled surface of the bolt rubs to force the bolt 20 back into the casing when the door is being slammed is made sufficiently wide to bridge the recesses 30 and thus provide for continuous wedging action against the bolt.

It will be appreciated from the foregoing 25 that the invention provides for the locking of the doors and the like with much greater safety than has heretofore been possible with the type of latch in question. It is to be understood, however, that the invention is 30 not limited to the precise constructional details set forth. For example, the ribs 22 and 23 may each have only one nick or recess, these nicks being so disposed as to be out of alignment with each other. The recessing of the bevelled face of the bolt may 35 also be varied considerably according to circumstances. The locking pin 28 may also be brought into operative position by movable members of an arrangement different 40 from that shown in Figures 5 and 6.

I claim:—

1. A door or like latch, comprising a locking-staple and a spring-bolt having a beveled surface which lies completely across the 45 depth of the bolt and rubs over the locking-staple to force the bolt back during the operation of the closing of the door or the like, said beveled surface being so recessed as to leave ribs at its upper and lower edges to form between them a channel, and to form between them a channel and so 50 that a portion of the beveled surface remains for presentation to a cooperating pressing surface on the locking-staple lying completely across the depth of the bolt, each 55 rib having a groove lying in a direction transverse to that in which the bolt rubs against the locking staple, which grooves open at their ends directed towards one another into said channel.
2. A door or like latch, comprising a locking-staple, a spring-bolt having a beveled surface which lies completely across the 60 depth of the bolt and is so recessed as to leave ribs at its upper and lower edges and to form between them a channel, and so that 65

a portion of the beveled surface remains for presentation to a cooperating pressing surface on the locking-staple lying completely across the depth of the bolt, and means operative in the said channel for arresting 70 relative movement, along the said beveled surface, in relation to the locking-staple of a pressing article of a width permitting it to enter the said channel.

3. A door or like latch comprising a bolt 75 with a bevelled surface which rubs over the locking staple of the latch to force the bolt back during the operation of the closing of the door or the like, a locking catch whereof a surface is exposed in the said bevelled 80 surface of the bolt, and means controlling said catch whereby it is arranged to "give" when pressure is applied to its said exposed surface and thus be brought into locking engagement with a stationary part of the 85 latch.

4. A door or like latch comprising a bolt with a recessed bevelled surface which rubs over the locking staple of the latch to force the bolt back during the operation of the closing of the door or the like, a locking catch whereof a surface is exposed at a recess in the said bevelled surface of the bolt, and means controlling said catch whereby 90 it is arranged to "give" when pressure is applied to its said exposed surface and thus be brought into locking engagement with the stationary part of the latch.

5. A door or like latch comprising a bolt with a bevelled surface which rubs over the 100 locking staple of the latch to force the bolt back during the operation of the closing of the door or the like, said bevelled surface being so recessed as to leave ribs at its upper and lower edges to form between them a 105 channel, a locking catch housed in said channel with a surface of it exposed in the bevelled surface of the bolt, and means controlling said catch whereby it is arranged to "give" when pressure is applied to its said exposed surface and thus be brought into locking engagement with the stationary part of the latch.

6. A door or like latch comprising a bolt with a bevelled surface which rubs over the 115 locking staple of the latch to force the bolt back during the operation of the closing of the door or the like, said bevelled surface being so recessed as to leave ribs at its upper and lower edges to form between them a 120 channel, and said ribs being stepped so as to constitute parts of other channels opening out at their opposite ends of the top and bottom faces of the bolt, a locking catch housed in said first-named channel with a 125 surface of it exposed in the bevelled surface of the bolt, and means controlling said catch whereby it is arranged to "give" when pressure is applied to its said exposed surface and thus be brought into locking engage- 130

ment with the stationary part of the latch.

7. A door or like latch comprising a bolt with a bevelled surface which rubs over the locking staple of the latch to force the bolt back during the operation of the closing of the door or the like, a spring tending to press said bolt towards its locking position, and a locking catch whereof a surface is exposed in the said bevelled surface of the bolt,

said spring controlling also said catch 10 whereby the latter is arranged to "give" when pressure is applied to its exposed surface and thus be brought into locking engagement with a stationary part of the latch.

15 In testimony whereof I affix my signature.

ETHEL MAY LAWRENCE.
